UNITED STATES PATENT OFFICE.

EDWARD H. MIX, OF STAMFORD, CONNECTICUT, ASSIGNOR TO THE YALE & TOWNE MANUFACTURING COMPANY, OF STAMFORD, CONNECTICUT.

CYLINDER FOR LOCKS.

SPECIFICATION forming part of Letters Patent No. 696,067, dated March 25, 1902.

Application filed November 28, 1898. Serial No. 697,667. (No model.)

To all whom it may concern:

Be it known that I, EDWARD H. MIX, a citizen of the United States, and a resident of Stamford, in the county of Fairfield and State 5 of Connecticut, (post-office address Stamford, Fairfield county, care of the Yale & Towne Manufacturing Company,) have invented certain new and useful Improvements in Key-Cylinders for Locks, of which the following is 10 a specification.

My invention relates to an improvement in key cylinders or nosings of locks, and it is applicable to any type of lock in which the locking and tumbler mechanisms are contained 15 in the lock-casing and in which the key cylinder or nosing is simply used as a support and guide for the key.

A detachable key-plug for locks of the above class has already been made, as shown in the 20 patent of F. W. Mix, No. 551,684; but in that instance the key-plug is not secured as in the present case, but has squared projection passed entirely through the lock-casing and having a bearing in its rear plate as well as 25 in its front plate and having a further bearing in the escutcheon attached to the drawer front or other closure; but in my improvement the key cylinder or nosing is made self-contained and is attached only to one wall of 30 the lock-casing and when in place needs no further support. A set-screw similar to that shown in patent of F. W. Mix, No. 524,643, is employed by me for holding the key-cylinder in place, but is used differently there- 35 from, since in the old use the set-screw holds the plug from sliding downward, out of engagement with the case, whereas in the present use the screw impinges a face to prevent disengaging rotation of the plug, the plug being 40 provided with a round neck that engages in a square hole and having a squared head that can pass through the hole, but engages the wall of the case when rotated forty-five degrees. The advantage of this construction 45 in connection with mortise-locks is obvious, because without a detachable key nosing or cylinder the mortise-lock cannot be applied; but it is also advantageous in connection with half mortise or rim locks, because the 50 lock-casings and locking mechanism of locks

may be made up in any desired quantity and carried in stock, while the key cylinders or nosings can be made of varying lengths for different thicknesses of wood and supplied to the users according to demand.

To these ends my invention consists in providing the lock-casing with an opening in the front wall of non-circular form, preferably polygonal; and a rotatable key cylinder or nosing which aids or supports the key during 60 rotation, with a neck located in the opening and with a non-circular head, preferably of the same shape as the opening in the lock-casing and which will enter the opening in the front wall and pass through it when presented thereto in proper position, but will engage with the front wall and thereafter prevent removal of the key-cylinder when the key-cylinder is turned upon its axis to a slight degree. The key-cylinder is retained in this 65 position by means of a set-screw or equivalent fastening device introduced from some part of the lock or closure which is accessible only when the door or closure is open, and this fastening device as well as the depression or opening which it enters in the key-cylinder are so positioned as to secure the key-cylinder in proper position to direct the key properly to the lock-actuating mechanism which is within the lock-casing proper. 70

My invention will be fully understood upon reference to the accompanying drawings, in which—

Figure 1 is a fragmentary view of a closure in which my improved rotating key-cylinder 85 is connected with the front wall of a lock, or a section thereof is shown mortised. Fig. 2 is a perspective view showing separated the lock-casing and the key-cylinder, the parts being in the relative positions which they assume when coming together and before the key-cylinder is turned to cause engagement. Fig. 2^a shows the key-cylinder in reverse position. Fig. 3 is a vertical section showing the inside of the front wall of the lock-casing 90 with the key-cylinder in position and the retaining-screw inserted.

1 represents the part of a door, desk-cover, or other closure to which a mortise cabinet-lock is generally applied.

2 represents a lock-casing which is mortised into the part 1 in the usual manner and secured by the face-plate 3.

4 represents a rotatable key-cylinder which 5 is likewise mortised into the part 1, but in a position which makes it imperative to have said key-cylinder separable from the lock-casing 2 in order to apply the parts, as shown.

My present invention provides means for 10 detachably connecting the key-cylinder to the lock-casing in a convenient, inexpensive, and effective manner, and consists in forming the lock-casing 2 with an opening 5 of other than circular shape, in order to admit an engaging 15 part which may thereafter be turned so as to engage the front wall of the lock-casing, and in providing the key-cylinder 4 with a head 6 at its inner end, which will readily enter the opening 5 when presented in proper position, but the corners 6^a of which will engage 20 the front walls of the lock-casing from behind when the key-cylinder is slightly rotated—say to ninety degrees—and thereafter prevent removal of the key-cylinder until the latter is 25 again turned to bring the sides of its head so as to coincide or register with the sides of the opening. A reduced neck 4^a is preferably formed on the inner end of the key-cylinder in rear of the head, so as to fit the shorter 30 diameter of the opening 5, and this, together with the impingement of the head 6 and the shoulder 4^b on the front wall of the lock-casing, will hold the key-cylinder firmly in position. To prevent rotation of the key-cylinder 35 to disengaging position after the parts are assembled, I employ a set-screw or pin 8, threaded at its outer end in the face-plate 3, as shown at 9, and having a bearing 10 for its inner end adjacent to the key-cylinder 4. 40 The end of the set-screw 8 enters a depression or recess 11 in the key-cylinder, which is so located as to cause the key-cylinder to as-

sume the proper position to direct the key properly to the locking mechanism within the lock-casing when the retaining-pin or set-screw is introduced. The outer end of the key-cylinder is formed with an annular seat 4^c for a rotating key piece or disk 12 and with radial notches 4^d. The key piece or disk 12 is provided with a diametric key-slot 12^a, whose ends are adapted to register with the radial notches 4^d when the key (not shown) is in proper position to enter the lock-casing.

Having thus described my invention, the 55 following is what I claim as new therein and desire to secure by Letters Patent:

1. The combination of a lock-casing having a non-circular opening, a key-plug, a flanged head at one end of said plug adapted to be 60 fitted in the opening of the casing and rotated with the plug to engage the inner wall of the casing, and means holding the plug in adjusted position.

2. The combination of a lock-casing having 65 a non-circular opening, a key-plug, a flanged head at one end of said plug adapted to be fitted in the opening of the casing and rotated with the plug to engage the inner wall of the casing, and a set-screw carried by the casing 70 and adapted to engage the rotatable plug.

3. The combination of a lock-casing, having a polygonal-shaped opening therein, a key-plug provided with a round neck of less diameter than the said opening, a polygonal-shaped flanged head on the plug, the corners 75 of which are adapted to engage with the inner walls of the casing, and means holding the plug in adjusted position.

EDW. H. MIX.
